CLAIM

The ornamental design for an autoinjector with removable cap, as shown and described.

DESCRIPTION

FIG. 1 is a perspective view showing a new design for an autoinjector with a removable cap having a cylindrical side profile, showing the removable cap disposed on the autoinjector;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view showing the autoinjector with removable cap of FIGS. 1-7 with the removable cap removed;

FIG. 9 is a perspective view showing an alternative new design for an autoinjector with a removable cap having a triangular shaped side profile, showing the removable cap disposed on the autoinjector;

FIG. 10 is a front elevation view thereof;

FIG. 11 is a rear elevation view thereof;

FIG. 12 is a left-side elevation view thereof;

FIG. 13 is a right-side elevation view thereof;

FIG. 14 is a top plan view thereof;

FIG. 15 is a bottom plan view thereof;

FIG. 16 is a perspective view showing the autoinjector with removable cap of FIGS. 9-15 with the removable cap removed;

FIG. 17 is a perspective view showing an alternative new design for an autoinjector with a removable cap having a flared side profile, showing the removable cap disposed on the autoinjector;

FIG. 18 is a front elevation view thereof;

FIG. 19 is a rear elevation view thereof;

FIG. 20 is a left-side elevation view thereof;

FIG. 21 is a right-side elevation view thereof;

FIG. 22 is a top plan view thereof;

FIG. 23 is a bottom plan view thereof; and,

(Continued)

FIG. 24 is a perspective view showing the autoinjector with removable cap of FIGS. 17-23 with the removable cap removed.

The dashed lines showing portions of the autoinjector drug delivery device are included for the purpose of illustrating environment and form no part of the claimed design.

The autoinjector with removable cap is shown with a symbolic break in its length. The appearance of any portion of the article between the break lines forms no part of the claimed design.
